Primary Examiner — Cynthia Ramirez*Assistant Examiner* — Laura H Yu(74) *Attorney, Agent, or Firm* — Banner & Witcoff, Ltd.(57) **CLAIM**

The ornamental design for a shoe, as shown and described.

DESCRIPTION

FIG. 1 is a top view of a shoe showing our new design,

FIG. 2 is a front view thereof;

FIG. 3 is a rear view thereof;

FIG. 4 is a first side view thereof;

FIG. 5 is a second side view thereof; and,

FIG. 6 is a front perspective view thereof.

The long-and-short broken lines form the boundary of the shoe and form no part of the claimed design. The even-length broken lines of the remainder of the shoe are environment and form no part of the claimed design.
